UNITED STATES PATENT OFFICE.

GEORG NOESSKE, OF BERLIN-STEGLITZ, GERMANY.

SWIMMING SHOE.

Application filed June 2, 1926, Serial No. 113,278, and in Germany June 9, 1925.

This invention relates to a swimming shoe with flap floats rockable about hinged joints.

According to the invention, arched pressure floats are arranged underneath the joint 5 provided at the level of the ankle in a rigid leg frame, and the inner float is of less breadth than the outer. The floats rockable about the joints may in a known manner be subdivided into flaps, the valve flaps according to the invention being arranged at different angles to the horizontal. The outer flap under these circumstances bears against a fixed stop on the frame, and each subsequent flap against the preceding one. As 10 compared with the known swimming shoes with a float rockable on one side above the joint the invention has the advantage that the pressure surface below the joint diminishes the lever arm acting on the natural 15 ankle joint to the smallest limits, while the transmission of pressure to the rigid frame is effected completely uniformly in all parts. The arched floats subdivided by valve flaps 20 enhance the pressure effect when treading water, and facilitate the gliding of the float 25 through the water when raising the shoe.

One constructional example of a swimming shoe constructed according to the invention is illustrated in the accompanying 30 drawings, wherein

Figure 1 is a side elevation,

Figure 2 a longitudinal section on the line II—II in Figure 1,

Figure 3 a plan view, and

Figure 4 an enlarged cross section through the left-hand float.

The swimming shoe shown consists according to the right-hand half of Figures 1 to 3 of splints or leg bars 1, which can be 40 secured in any convenient manner to the legs, and are preferably made of rigid material. The under part 3 of the shoe is pivoted at 2 on each side with an inflexible joint in such a way that it can be rocked in the direction of the arrow 4 in Figure 1. To the 45 under part 3, which is provided with bridge pieces 5 extending under the sole and the heel in the form of a U, a rather wide float 7 is pivoted at 6 outside and a narrower float 50 7 inside. The floats 7 are held in a known manner by springs 8 in the outstretched position illustrated, and are prevented from stretching further by chains or cords 9, which engage with outer margins at 10, and 55 are hooked into the foot member 3, 5 at 11. When the swimmer draws in his foot, the

floats 7 move downwards owing to the water pressure against the pressure of the springs 8, and take up the position shown in dotted lines in Figure 4, until the foot is stretched 60 again, whereupon the water pressure acts in the reverse direction and presses the floats into the extended position again, with the assistance of the springs 8. By the joints 2 arranged at right angles to the joints 6 65 and 6' the swimmer can impart to the floats, in relation to the longitudinal direction, a different push-and-pull position, and the foot itself remains, notwithstanding the rigid swimming shoe which is advantageous 70 for the swimming action, movable and flexible, which is very important for the purpose of obviating the cramp that frequently occurs in swimming.

Each of the floats 7 consists, in the left-hand half of Figures 2, 3 and 4, of a series of float elements 7', which are rockable in a vertical direction about hinges 6', each of the inner float members 7' always bearing with its free margin against the adjacent hinge from below, so that the separate parts of the float always have different inclinations to the horizontal. The outer float bears in the working position against a special stop 7''. The entire float may be fixedly 80 connected with the under part 3, or may be secured thereto by a hinge in the longitudinal direction. In this case the upward movement of the float as a whole is limited 85 by cords or belts 9.

During the upward movement of the foot the comparatively small float members 7' are directly pressed downwards by the water pressure, and yield much more quickly than a large float with a pressure plate consisting 90 of one piece, so that the wearer of the swimming shoe hardly becomes aware of the light passage of the shoe through the water. Now when he presses the shoe downwards again 95 the small floats likewise close again much more easily and instantly restore an uninterrupted pressure surface, so that here again the contemplated pressure action occurs much more promptly, and an idle part of the down stroke of the shoe is avoided, this 100 result being specially assisted by the arched arrangement of the float members.

What I claim is:—

1. A swimming shoe, comprising a rigid leg frame jointed at the level of the wearer's 110 angle, and arched valve floats hinged to said leg frame below the ankle joint.

2. A swimming shoe, comprising a rigid leg frame jointed at the level of the wearer's ankle, and an arched valve float hinged to each side of said leg frame below the ankle joint, the inner float being narrower than the outer float.
3. A swimming shoe, comprising a rigid leg frame jointed at the level of the wearer's ankle, and an arched valve float hinged to 10 said leg frame below the ankle joint, said valve float comprising a plurality of flaps arranged at different inclinations to the horizontal.
4. A swimming shoe, comprising a rigid 15 leg frame jointed at the level of the wearer's ankle, an arched valve float hinged to each side of said leg frame below the ankle joint, the inner float being narrower than the outer float, and said outer float comprising a plurality of flaps arranged at different inclinations to the horizontal.
5. A swimming shoe, comprising a rigid leg frame jointed at the level of the wearer's ankle, an arched valve float hinged to said leg frame below the ankle joint, said valve 25 float comprising a plurality of flaps arranged at different inclinations to the horizontal, and a fixed abutment to limit the oscillation of the outermost of said flaps.
6. A swimming shoe, comprising a rigid 30 leg frame jointed at the level of the wearer's ankle, an arched valve float hinged to each side of said leg frame below the ankle joint, the inner float being narrower than the outer float, said outer float comprising a plurality 35 of flaps arranged at different inclinations to the horizontal, and a fixed abutment to limit the oscillation of the outermost of said flaps.

In testimony whereof I have signed my name to this specification.

GEORG NOESSKE.
